The ornamental design for a blow molded fire resistant safe, as shown and described.

DESCRIPTION

FIG. 1 is a right front perspective view of a blow molded fire resistant safe according to the present invention;

FIG. 2 is a front view of the blow molded fire resistant safe shown in FIG. 1;

FIG. 3 is a left side view of the blow molded fire resistant safe shown in FIG. 1;

FIG. 4 is a right side view of the blow molded fire resistant safe shown in FIG. 1;

FIG. 5 is a top view of the blow molded fire resistant safe shown in FIG. 1;

FIG. 6 is a bottom view of the blow molded fire resistant safe shown in FIG. 1;

FIG. 7 is a rear view of the blow molded fire resistant safe shown in FIG. 1; and,

FIG. 8 is a left rear perspective view of the blow molded fire resistant safe in FIG. 1.
